MINE CAR BUMPER

Victor Willoughby, Ridgewood, N. J., assignor to
American Car and Foundry Company, New
York, N. Y., a corporation of New Jersey

Application May 20, 1937, Serial No. 143,681

21 Claims. (Cl. 105—364)

This invention relates to bumpers for mine and industrial type cars or any other type of cars which are link coupled together. Previous constructions have caused considerable damage to the coupling links due to the crushing of these links when the cars came together on buff.

It is an object, therefore, of this invention to provide a bumper which will positively throw the coupler link to one side preventing its being crushed.

A further object of the invention is the provision of a bumper and coupler arrangement in which the coupling link will be positively forced to one side and clear the bumper face, thus preventing its being crushed.

A still further object of the invention is the provision of a new and improved support for use between the coupling straps of a mine or other car.

These and other objects of the invention will be apparent to persons skilled in the art from a study of the following description and accompanying drawings, in which:

Figure 1 is a plan view of the improved end construction and bumper;

Fig. 2 is a sectional view taken substantially on line 2—2 of Fig. 3;

Fig. 3 is a sectional view taken substantially on line 3—3 of Fig. 2;

Fig. 4 is a plan view of the bumper and showing the position of the coupling link when under tension and without tension;

Fig. 5 is a front elevational view of the bumper with the link in the various positions as indicated in Fig. 4, and

Fig. 6 is a perspective view of the improved filler block or casting.

Referring now to the drawings in detail, it is seen that the end construction has been applied to a car having Z section side sills 2 upon which the customary side and central floors 4 and 6 respectively are secured. The end construction is composed of a plurality of plates, one of which has a rear horizontal portion 8 adapted to be secured to the central floor and inturned flanges of the side sill. This plate is also formed with an upwardly inclined portion 10 terminating throughout the major portion thereof in a downwardly directed vertically extending flange 12 adapted to be secured by means, such as rivets 14, to the vertical web 16 of a Z formed end member. As clearly shown in Figs. 2 and 3 the central portion of this plate is pressed inwardly in order to provide a groove for the lower strap 18 of the drawbar or strap coupling. The Z formed

end member has an outwardly directed top flange 20 to which is secured the upper horizontal buffering plate 22 of the end extension. This plate overlies the lower drawbar 18 which extends through a notch cut in the Z end member as is clearly shown in Fig. 2. The lower inwardly directed flange 24 of the Z end member has secured thereto a lower horizontal buffering plate 26, which extends outwardly beyond the end of the side sills and is supported outwardly of the Z 10 member by means of a conventional form of end strap or binder 28.

The strap coupling or drawbar is completed by securing an upper bar 29 to the central floor and to the inclined end plate and lower strap 18. In order to provide space to receive the coupling linkage, this upper drawbar strap is deflected upwardly as at 30 and then horizontally outward as at 32 in spaced relation to the upper buffering plate and lower drawbar strap. It is obvious that unless supported, this upper portion would be distorted under draft forces, and accordingly some type of filler block or casting is necessary. In the present instance the filler block 34 is shown as made of a single casting having upper, lower 25 and rear surfaces conforming to the shape of the upper and lower drawbar straps and side walls 36 which converge forwardly to an apex 38; the resulting construction providing a filler block of generally wedge shape. The apex 38 is substantially on the center line of the casting and immediately ahead of the opening 40 through which the securing and anchoring bolt 42 extends. Any rotational movement of the filler block about this bolt is prevented due to rearwardly projecting 30 lugs 44 which closely engage the sides of the inclined portion 30 of the upper drawbar strap as clearly shown in Figs. 1 and 2.

The space between the upper and lower horizontal buffering plates is adapted to be filled with wood or other buffering blocks 46 which extend outwardly beyond the ends of the plates and bear against the inner face of the bumper cap 48. The bumper cap in the instance shown is pressed or otherwise formed with a curved buffering or face 45 plate 50 and rearwardly directed upper and lower horizontal flanges 52 and 54 respectively adapted to overlie the upper and lower horizontal buffering plates of the end construction. The bumper cap is secured in position on the end construction 50 by means of bolts or other means 56 which extend through the upper and lower buffering plates and wood blocks. In order to provide for coupling of cars the upper and lower drawbar straps, as well as the upper and lower flanges of the 55

end construction and bumper cap, are provided with aligned openings through which coupling pin or bolt 58 may extend, with its center substantially in alignment with the center line of the drawbar straps and directly outward of the filler casting apex. The bumper cap is formed with an upwardly extending, rounded projection 60 which is located to one side or the other of the center line of the drawbar and is so positioned that its axis will be at angle to this center line and preferably intersects the center line at the center of the coupling pin or bolt as is clearly shown in Fig. 4. This projection may be either pressed in the bumper top flange 52 or formed by welding a short piece of round stock to the bumper top flange.

With the previously described construction it is obvious that when the car is being pulled the draw link 62 will be in the position as shown by full lines in Figs. 1 and 2 and by line and dash in Figs. 4 and 5. In this position the link is raised vertically and spaced from the bumper flanges with one side of the link resting upon the top of the projection 60. When the draft is released and the cars start toward each other on a buffing action the link will, of course, be thrown to one side by the projection and will assume the position shown in full lines on Figs. 4 and 5. With the link thrown to one side and the cars continuing their buff action, the link will be moved backward until the rear portion contacts one of the diverging walls of the filler casting which will further throw the link to one side and into the position shown by line and dash in Fig. 5. 1. In cases where the buff action might take place as the car was rounding a curve and the coupling link resting substantially at right angles to the axis of the projection, the projection would, of course, have no effect in throwing the link to one side, but with the link in this angular position as it moves backward it would again be deflected by one of the diverging walls of the filler block and would assume the position shown by line and double dash of Fig. 1. It is thus seen that regardless of the position of the coupling link upon the commencement of the buffing action the link will be thrown to one side or the other, thus preventing its being crushed and that the bumper projection and improved filler casting cooperate to accomplish this result.

While the invention has been described more or less in detail, it is obvious that various modifications and rearrangements of parts will be possible and all such modifications and rearrangements of parts are contemplated as fall within the scope of the following claims:

What is claimed is:

1. In a mine or similar rail car, the combination of a metal bumper, a drawbar located at least in part above the bumper and formed with upper and lower spaced jaws adapted to receive a coupling link therebetween, a coupling link between said jaws, said bumper comprising an upright buffing face and an upper flange directed toward the car body and overlying the lower jaw of said drawbar, said upper flange being formed with an upwardly extending, rounded projection normally supporting the coupling link in spaced relation to the bumper during application of draft forces to the link.

2. In a mine or similar rail car, the combination of a metal bumper, a drawbar located at least in part above the bumper and formed with spaced jaws to receive a coupling link therebetween, a coupling link between said jaws, said bumper

comprising an upright buffing face and an upper flange directed toward the car body, said upper flange being formed with an upwardly extending, rounded projection normally supporting the coupling link in spaced relation to the bumper during application of draft forces to the link, said projection being of such a length and arranged at an angle to the vertical center plane of the bumper in such a position that said link will be deflected thereby to one side thereof upon cessation of the application of the draft forces. 10

3. In a mine or similar rail car, the combination of a metal bumper, a drawbar located at least in part above the bumper and formed with spaced jaws adapted to receive a coupling link therebetween, a coupling link between said jaws, a filler block arranged rearwardly of said link and positioned between said jaws to maintain their spaced relationship, said link being adapted to contact said filler block when moved inwardly under buffing forces, the bumper comprising an upright buffing face and an upper flange directed toward the car body, the upper flange being formed with an upwardly extending projection normally supporting the coupling link in spaced relation to the bumper during application of draft forces to said link, the projection having its longer dimension of such a length and arranged at such an angle to the vertical center plane of the bumper that said link will be deflected thereby to one side thereof upon cessation of draft forces, said filler block being provided with a wedge-shaped face with the apex thereof in a vertical plane intersecting the longitudinal axis of said drawbar to further deflect 30 said link upon contact therewith. 35

4. In a mine or similar rail car, the combination of a metal bumper, a drawbar located at least in part above the bumper and formed with spaced jaws to receive a coupling link therebetween, a coupling link between said jaws, a spacing block arranged rearwardly of said link and positioned between said jaws to maintain their spaced relationship, said link being adapted to contact said block when moved inwardly under buffing forces, said block being formed with a wedge-shaped face having the apex thereof disposed in a vertical plane intersecting the longitudinal axis of said drawbar to deflect said link upon contact therewith. 40

5. In a mine or similar rail car, the combination of a metal bumper, a drawbar located at least in part above the bumper and formed with spaced jaws to receive a coupling link therebetween, a coupling link between said jaws, a spacing block arranged rearwardly of said link and positioned between said jaws to maintain their spaced relationship, said link being adapted to contact said block when moved inwardly under buffing forces, said block being formed with a wedge-shaped face having the apex thereof disposed in a vertical plane intersecting the longitudinal axis of said drawbar to deflect said link upon contact therewith, and projections on said block engageable with the jaws to prevent lateral 60 displacement of the block. 65

6. In a mine or similar rail car, the combination of a metal bumper, a drawbar located at least in part above the bumper and formed with spaced jaws to receive a coupling link therebetween, a coupling link retained between said jaws by a coupling pin, said bumper comprising an upright buffing face and an upper flange directed toward the car body, said upper flange 70 75

being formed with an upwardly extending, elongated, rounded projection normally supporting the coupling link in spaced relation to the bumper flange during application of draft forces to the link, said projection being of such length and having the longitudinal axis thereof intersecting the coupling pin at an angle to the center line of the car in such a position that said link will be deflected by said projection to one side of the latter upon cessation of the application of the draft forces.

7. In a mine or similar rail car, the combination of a metal bumper, a drawbar located at least in part above the bumper and formed with spaced jaws to receive a coupling link therebetween, a coupling link retained between said jaws by a coupling pin, said bumper comprising an upright buffing face and an upper flange directed toward the car body, said upper flange being formed with an upwardly extending elongated, projection normally supporting the coupling link in spaced relation to the bumper flange during application of draft forces to the link, said projection being of such length and having the longitudinal axis thereof intersecting the coupling pin at such an angle to the center line of the car that said link will be deflected to one side of the projection upon cessation of the application of the draft forces, and a filler block between the spaced jaws formed with a wedge-shaped face having the apex thereof disposed substantially in the vertical plane of the longitudinal axis of the drawbar, said link being shiftable inwardly into contact with said block under buffing forces to which the car is subjected to be further deflected by said wedge-shaped face.

8. As an article of manufacture, a bumper for mine cars comprising, a buffing face curved rearwardly from either side of the vertical transverse center plane of the bumper, an upper rearwardly directed flange joined to the curved face at its upper edge, and an elongated, rounded projection on said flange, said projection being positioned adjacent one side of the vertical center plane of the bumper with its longitudinal axis at an angle thereto and being so formed as to deflect a coupling link upon cessation of draft forces to which said link is subjected.

9. As an article of manufacture, a filler block for use between the spaced jaws of a drawbar comprising, upper, lower and rear surfaces conforming substantially to the jaws of the drawbar, and forward surfaces formed by walls converging to an apex located substantially in the vertical plane through the longitudinal center of the block.

10. A bumper for mine or similar cars comprising spaced upper and lower flanges and an intermediate face plate, said upper flange having on its upper surface a rounded and elongated projection positioned adjacent the vertical center plane of said bumper with the longitudinal axis thereof intersecting said vertical center plane, said projection being so formed and arranged that a coupling link will be deflected thereby upon cessation of draft forces to which the link is subjected.

11. A bumper for mine or similar cars comprising an upright buffing plate, a longitudinal flange extending from said plate at its upper edge, and an elongated projection on the upper surface of said flange, said projection being positioned at an angle to the transverse center line of said bumper and so formed and arranged that a

coupling link will be deflected thereby upon cessation of draft forces to which the link is subjected.

12. In a mine or similar rail car, the combination of a metal bumper, a drawbar located at least in part above the bumper and formed with spaced jaws, a coupling link between said jaws, said bumper comprising an upright buffing face and an upper flange directed toward the car body, and a projection on said upper flange adapted to support the coupling link in spaced relation to the bumper during application of draft forces to the link, said projection being so formed and arranged as to cause said link to be deflected to one side upon cessation of said draft forces.

13. A filler block for use between the spaced jaws of a drawbar comprising upper, lower and rear faces conforming substantially to the jaws of the drawbar, said filler block being provided with a wedge-shaped forward portion having the apex thereof disposed in a vertical plane passing through the longitudinal center of said block.

14. In a mine or similar rail car, the combination of a metal bumper, a drawbar located at least in part above the bumper and formed with spaced jaws, an inwardly shiftable coupling link between said jaws, and a filler block between said jaws to maintain their spaced relationship, said block being so formed and arranged as to cause said link to be deflected to one side of the jaws during inward movement of the link under buffing forces.

15. In a mine or similar rail car, the combination of a metal bumper, a drawbar located at least in part above the bumper and formed with spaced jaws, a coupling link between said jaws, said bumper comprising an upright buffing face and an upper flange directed toward the car body, and means on said upper flange so formed and arranged as to support the coupling link in spaced relation to the bumper during application of draft forces to the link and to cause said link to be deflected to one side upon cessation of said draft forces, said means comprising an elongated, projection formed on said upper flange and arranged at an angle to the vertical center plane of the bumper.

16. In a mine or similar rail car, a metal bumper comprising an upright bumping face and an upper flange, a drawbar having at least a part thereof arranged in spaced relation above the bumper and formed with spaced jaws for receiving a coupling link therebetween, a projection on said upper flange for supporting the coupling link in spaced relation to said flange during application of draft forces, said projection being so formed and arranged as to cause said coupling link to be deflected to a position crossing the longitudinal center line of the bumper upon cessation of said draft forces.

17. A filler block for use between spaced jaws of a draw bar comprising a body portion having forwardly converging side walls.

18. A filler block for use between spaced jaws of a draw bar comprising a body portion having a wedge shaped forward portion formed forwardly converging side walls, and spaced lugs projecting from the rear portion of said block.

19. A bumper for mine or similar cars, comprising spaced upper and lower flanges and a face plate, said upper flange having an elongated projection on its upper surface positioned adjacent and at an acute angle to the vertical center plane of said bumper and so formed and arranged that

a coupling link will be deflected thereby upon cessation of draft forces to which the link is subjected.

- 5 20. A bumper for mine or similar cars, comprising an upright buffing plate, a longitudinal flange extending from said plate at its upper edge portion, and an elongated projection on the upper surface of said flange adjacent its junction with the buffing plate, said projection being positioned at an acute angle to the transverse center line of said bumper and so formed and arranged that a coupling link will be deflected thereby upon cessation of draft forces to which the link is subjected.
- 10

21. As an article of manufacture, a bumper for mine cars or the like comprising a curved buffing face, an upper flange joined to the upper portion of the buffing face, and a projection arranged on the upper surface of the upper flange in such position that the plane of its longitudinal axis intersects a vertical plane through the upper flange at a point substantially intermediate the end portions of said upper flange and being so formed that a coupling link will be deflected thereby upon cessation of draft forces to which the link is subjected.

5 10 VICTOR WILLOUGHBY.
